UNITED STATES PATENT OFFICE.

DONALD S. BARROWS, OF ROCHESTER, NEW YORK, ASSIGNEE, BY MESNE ASSIGNMENTS TO THE SYMINGTON COMPANY, A CORPORATION OF MARYLAND.

LOCKING LID FOR JOURNAL BOXES.

Application filed March 17, 1920. Serial No. 386,567.

To all whom it may concern:

Be it known that I, DONALD S. BARROWS, a citizen of the United States, residing at Rochester, in the county of Monroe and State of New York, have invented certain new and useful Improvements in Locking Lids for Journal Boxes; and I do hereby declare the following to be a full, clear, and exact description of the invention, such as will enable others skilled in the art to which it appertains to make and use the same.

My invention relates to journal boxes and more particularly to locking means for use in connection with journal box lids of the vertically swinging type now so commonly employed.

The principal object of my invention, broadly stated, is to provide a strong, simple and inexpensive locking device for use with the type of lids above set forth.

Another object of the invention is to provide a locking mechanism for journal box lids which will positively maintain the lids in closed position, and which while simple in form and easy to operate, does not require a special tool or key to operate the locking mechanism.

A still further object of the invention is to operatively connect the locking mechanism to the journal box lid by means integral with one or both of said members whereby all danger of the parts becoming separated is avoided.

Other objects of the invention will appear hereinafter in connection with the detailed description of the preferred embodiment of my device which has been illustrated in the accompanying drawings, in which,—

Figure 1 is a vertical sectional view of a journal box lid showing the invention applied thereto and showing the adjacent portion of the journal box.

Figs. 2 and 3 are, respectively, rear and front elevations of a journal box lid having the invention applied thereto, and

Fig. 4 is a fragmentary view of a portion of the journal box lid showing one of the brackets for the trunnion of the locking member.

Throughout the specification and drawings like parts are designated by like reference characters.

The numeral 1 designates the journal box, only a portion of which is shown, to which

the improved locking lid 2 is pivotally connected, as for example by the pin 3 which passes through suitable ears on the lid 2 and through the opening 4 in the box lug 5.

For convenience I have illustrated the improved lid as provided with the well known Symington torsion spring mechanism for maintaining the same in open or closed position. It will, of course, be understood that I do not limit my invention to this type of spring mechanism and that my improved lid may be used with any form of spring mechanism as may be found desirable. The form of spring mechanism shown comprises a U-shaped spring member provided intermediate the end of each arm 6 and the body portion 7 with a loop or coil 8. The ends of the arms 6 are engaged behind lugs 9 provided on the inner face of the lid 2 and the body of the spring member bears against the outer face of the box lug 5. When the lid is assembled the spring member is placed under torsional stress so that in closed position, the spring arms 6 exert an inward pull on the lid and tend to hold the same in closed position. When the lid is raised to full open position the upper end of the spring member drops into the slight depression 5^a and tends to hold the lid raised.

Adjacent its lower end the lid 2 is provided with a longitudinally extending boss, which may be centrally arranged and which provides on the inner face of the lid a recess 10 adapted to receive the locking member 11. The said locking member is provided at the end of the arm 12 thereof with an enlarged head 13 having a downwardly extending locking lip 14 and an upwardly extending spring bearing face 15, which may be provided with a spring centering lug 16. The other arm 17 of the locking member 11 extends downwardly from the pivotal point of the locking member and is adapted at its extreme end to project from the recess 10 to afford means for releasing the locking lip or latch 14. It will be observed that the locking member is substantially U-shaped, the base of the U being formed by the body portion of the member 11 from which the pivot trunnions 18 extend, the latter being adapted to seat within the recess 18^a which is provided on the side walls of the recess 10.

The walls 18^b of the recesses 18^a are adapt-

ed to be bent as shown in Fig. 1 so as to partially embrace the trunnions 18 of the locking member 11 to securely hold the said member in position.

5 The locking lip 14 is maintained in engagement with the locking shoulder 19 of the journal box primarily by the spring 20 which is interposed between the bearing face 15 of the head 13 and the inner face of the 10 lid 2 on which may be provided a centering boss 21. The enlarged head 13 will fall to locking position by gravity should the spring 20 become lost or broken or should the same have its temper withdrawn due to 15 the heat generated within the journal box when the packing therein catches on fire.

To operate the locking device a tool is inserted between the arm 17 and the adjacent portion of the lid and the arm 17 pried toward the journal box, thus forcing the locking lip 14 out of engagement with the box shoulder 19 after which the lid is raised in the usual manner.

It has been found in practice that this 25 type of locking device affords a large measure of protection against unauthorized opening of the journal boxes and at the same time renders it unnecessary to supply trainmen with a special key to unlock the 30 journal box lid.

What I claim is:—

1. The combination with a journal box of a lid pivoted thereto, spring mechanism for maintaining said lid in open and closed 35 positions, and independent spring actuated means for locking the lid in closed position, said means comprising a member pivoted intermediate its ends to the inner face said lid, one end of said member extending below 40 the said pivot and being movable toward the adjacent portion of said box to release the lock.

2. The combination with a journal box, of

a vertically swinging lid pivoted thereto, 45 spring mechanism for maintaining said lid in open and closed positions, and locking means carried by the said lid for maintaining said lid in closed position, said means comprising a U-shaped member pivotally 50 connected to the inner face of said lid intermediate the ends of said member, one arm of said member serving as a locking member, the other arm extending downwardly from the point of pivotal connection substantially parallel with said lid and being adapted to be moved away from the 55 said lid in order to release the said locking member.

3. The combination with a journal box, of a lid pivoted thereto and adapted to close 60 the open end thereof, said lid having adjacent its lower end a recess opening on the rear face of the said lid and extending, when the lid is closed, below the opening in the said box, and means for locking said 65 lid in closed position, said means comprising a substantially U-shaped member pivotally connected to the said lid within the said recess, one arm of the said member engaging a portion of the said box, a spring interposed between the lid and a portion of the 70 said arm, the other arm of the said member extending downwardly and serving as means for releasing the engagement between said other arm and box. 75

4. The combination with a journal box, of a lid pivoted thereto, a spring mechanism for maintaining said lid in closed position and a spring pressed locking member pivotally carried by the said lid, and means 80 integral with the said lid and bendable into a position to positively engage a portion of the locking member to prevent its removal from said lid.

In testimony whereof I affix my signature.

DONALD S. BARROWS.
